UNITED STATES PATENT OFFICE.

MILTON L. TRESTER, OF LINCOLN, NEBRASKA.

INCUBATOR.

SPECIFICATION forming part of Letters Patent No. 672,155, dated April 16, 1901.

Application filed October 2, 1900. Serial No. 31,762. (No model.)

To all whom it may concern.

Be it known that I, MILTON L. TRESTER, a citizen of the United States, residing at Lincoln, in the county of Lancaster and State of Nebraska, have invented a new and useful 5 Incubator, of which the following is a specification.

The invention relates to improvements in incubators.

One object of the present invention is to improve the construction of incubators and to provide a simple and comparatively inexpensive one adapted to be uniformly heated at a minimum cost and capable of supplying 10 the egg chamber or compartment with pure moist air and of uniformly distributing the same throughout the incubator, so that it will be thoroughly diffused around the eggs.

Another object of the invention is to enable 20 the amount of moist air to be readily controlled and to arrange the water-receptacle on the exterior of the incubator, so that it will be surrounded by pure air and at the same time be readily accessible.

The invention consists in the construction 25 and novel combination and arrangement of parts hereinafter fully described, illustrated in the accompanying drawings, and pointed out in the claims hereto appended.

In the drawings, Figure 1 is a vertical sectional view of an incubator constructed in accordance with this invention. Fig. 2 is a 30 horizontal sectional view on line 2 2 of Fig. 1. Fig. 3 is a similar view on line 3 3 of Fig. 1.

Like numerals of reference designate corresponding parts in all the figures of the drawings.

1 designates a cylindrical body or casing provided at its top and sides with a lining of 40 mineral wool or other suitable material, which will render the walls and top impervious to air, and the said body or casing is designed to be supplied with suitable trays for the reception of the eggs to be hatched. The trays, 45 as indicated in Fig. 1 of the accompanying drawings, are designed to be located in the lower portion of the body or casing, and they may be disposed in any suitable manner, but are preferably annular to conform to the configuration of the casing. In practice the trays 50 will be preferably mounted for rotation in order that all portions of the trays may be

readily brought around to the door of the casing, and they may be constructed of sections to facilitate their ready removal.

55

Within the casing, at the top thereof, is arranged a drum 2 of substantially the same area as the top of the casing and located directly beneath the lining of mineral wool, as clearly illustrated in Fig. 2 of the accompanying drawings, and provided with a central vertical flue 6, extending downward from the bottom of the drum through an opening in the bottom of the casing and depending a considerable distance below the latter. The 60 lower end of the flue 6 hangs over a common coal-oil lamp or other suitable heating device, the heat passing upward through the flue 6, and the upward draft of hot air acquires considerable force before it enters the drum at 65 the top of the body or casing. Within the hot-air drum 2, which is shallow, is arranged a series of radially-disposed curved flanges or partitions 8, disposed substantially similar to the blades of a turbine wheel and adapted 70 to throw the hot air outward and cause the circulation of the same, whereby the drum will be uniformly heated. The hot air passing upward through the flue will force the hot air outward through the spaces between 75 the curved walls or partitions 8, so that a positive circulation is effected. The top of the drum is provided at intervals with openings 9, located near the outer wall or periphery of the drum, which is also provided with a central opening, from which extends a short pipe 10, located in alignment with the flue 6. A damper 11 is arranged above the short pipe 10, which forms the upper section of the flue, and the said damper 80 is hung from one end of a lever 11^a, which is fulcrumed near its outer end in suitable bearings of a support 4. The outer end of the lever is connected by a rod 11^b with a thermostat 12, located in the egg compartment or 85 chamber, as clearly shown in Fig. 1. When the damper is raised and the upper end of the pipe 10 is open, the heat passes directly out through the flue and does not enter the hot-air drum or heat the incubator; but when the 90 damper is closed the heat is whirled around in the drum and is thoroughly utilized before it is permitted to escape. The heat escapes 95 at the periphery of the drum through short 100

vertical outer flues or pipes 9^a, extending upward from the openings 9 through the top wall of the body or casing. The thermostat 12 may be constructed of any different kinds 5 of metal of unequal expansion and contraction of the heat and cold, aluminium and steel being preferred. The two strips of metal are riveted, soldered, or otherwise secured together, and the thermostat, which is approximately U-shaped, is doubled between its ends to provide the necessary length of material and to arrange it compactly within 10 the incubator. One end of the thermostat is secured to the casing by screws or other suitable fastening devices, and the other end is connected with the lower end of the rod 11^b. The end of the thermostat, which is bolted or otherwise secured to the casing, is bent at an angle, and the upper and lower sides of the 15 said thermostat are arranged as close together as possible without actually touching. The metals may be arranged to pull the rod upward or downward, and when it is desired to pull downward on the lever the metal which 20 expands the most is arranged inside the thermostat. If it is desired to move the rod upward to effect the closing of the damper, the metals are reversed, the one having the greatest expansion being arranged on the exterior 25 of the thermostat. The rod 11^b has its upper end threaded for the reception of an adjusting-nut 11^c, whereby the operation of the damper by the thermostat may be readily controlled.

30 Beneath the hot-air drum is arranged a device for distributing pure moist air to the egg compartment or chamber, and this distributor 16 consists of a circular bottom 17, spaced from the bottom of the hot-air drum by a series of curved strips or partitions 18, arranged similar to the curved walls or partitions of the hot-air drum and like the blades of a turbine wheel, and these curved walls or partitions are adapted to cause a circulation of 35 pure fresh air, which is warmed by the means hereinafter described before it is delivered into the egg compartment or chamber. The curved walls or flanges of the distributor 16 cause a radial circulation of the pure fresh 40 air, which is thoroughly diffused throughout the egg-chamber and around the eggs, and the said walls or flanges 18, which form the partitions of the distributor, may be disposed in the same general direction as the walls or 45 partitions of the drum or they may be reversely arranged. The horizontal pure-air distributor terminates short of the outer wall of the drum, and its top wall is formed by the 50 said drum.

55 The pure fresh air enters at the bottom of the incubator through short concentric tubes 19 and 20, spaced from the central flue and forming inner and outer passages, and the bottom of the distributor is provided at the 60 upper ends of the said passages with inner and outer perforations 21 and 22. The concentric tubes, which communicate with the

interior of the distributor 16, form jackets around the flue and assist in preventing the central portion of the incubator from being 70 excessively heated by the hot air passing upward from the flue to the drum, and the air passing upward through the concentric tubes 19 and 20 is heated before entering the distributor. The air in the inner tube 19 will be 75 heated to a higher degree than the air which passes upward through the outer tube 20; but the air from both of these tubes 19 and 20 will commingle in the distributor before entering the egg compartment or chamber. 80

The desired amount of moisture is supplied to the interior of the incubator by means of a vertically-adjustable receptacle or pan 24, mounted on the lower depending portion of the flue and provided with a centrally-arranged sleeve 25, extending upward from the bottom of the pan or receptacle and fitting on the said flue. The frictional engagement of the pan, or rather the sleeve 25 thereof, with the flue is sufficient to hold it at any desired 85 adjustment; but a set-screw or any other suitable fastening device may be provided for positively clamping or fastening the pan at the desired elevation. The air passing upward through the inner and outer concentric tubes will pass over the open mouth of the pan or receptacle 24 and will carry the moisture upward into the incubator. 90

The foul air which drops to the bottom of the body or compartment passes outward 100 through numerous openings 27, extending through the walls of the body or casing. The escape of the foul air is controlled by an exterior band 28, arranged on the casing or body a short distance above the bottom thereof 105 and provided with openings 29, adapted to register to a greater or less extent with the openings 27, whereby the size of the ventilating-openings may be changed. The ring or band 28 is adapted to slide around the casing or body, and it is designed to be provided with a set-screw or other suitable device for holding it in its adjusted position. By adjusting the band on the exterior of the body or casing the supply of fresh air through the 110 inner and outer concentric tubes is controlled and such pure fresh air may be supplied to the egg chamber or compartment at such times and in such quantities as the operator desires, and it is thoroughly and uniformly 115 diffused throughout the egg-chamber and around the eggs by the turbine arrangement of walls or partitions within the distributor 16. 120

It will be seen that the devices for distributing the hot air and the pure fresh warm 125 air are simple and comparatively inexpensive in construction, that the hot air is introduced into the incubator at the center thereof without excessively heating the incubator at that point, and that the eggs are compactly 130 arranged around the central flue and are brought closer to the source of heat, whereby a small amount of heat is required and the cost of heating reduced to a minimum. It

will also be apparent that the egg chamber or compartment may be maintained at a uniform temperature and that the parts may be readily adjusted to control the temperature of the 5 said egg chamber or compartment. Furthermore, it will be apparent that by arranging the water pan or receptacle on the exterior of the incubator it is always surrounded by pure air and is readily accessible and that it 10 may be readily adjusted vertically to control the amount of moisture carried upward by the fresh air.

What I claim is—

1. In an incubator, the combination of a 15 casing, a hot-air flue extending through the bottom of the casing, a hot-air drum located within the casing and connected with the flue and provided with curved partitions arranged radially, said drum being also connected with 20 the exterior of the said casing, and means for controlling the passage of the hot air, substantially as and for the purpose described.

2. In an incubator, the combination of a 25 casing, a hot-air flue extending through the casing, a hot-air drum centrally connected with the flue and arranged within the casing and provided with radial partitions and having outlets at its periphery extending through the casing, and means for controlling the 30 passage of the hot air, to cause the same to pass directly through the flue or to circulate through the drum, substantially as described.

3. In an incubator, the combination of a 35 casing, a hot-air drum located within the casing and provided with curved partitions arranged radially, the hot-air flue 6 extending through the bottom of the casing and connected with the drum, the short pipe 10 extending from the drum through the top of the 40 casing, the pure-air distributer arranged horizontally to meet the drum and terminating short of the outer walls thereof and provided with partitions, and a sleeve surrounding the hot-air tube 6 and connected with the pure- 45 air distributer, substantially as described.

4. In a device of the class described, the combination of a casing, a hot-air flue, a hot-air drum, a pure-air distributer arranged beneath the drum and provided with radial partitions and being open at its periphery, and the concentric tubes surrounding the flue and forming passages communicating with the distributer, substantially as described.

5. In an incubator, the combination of a 55 casing, a hot-air drum having top, bottom and side walls and arranged within the casing, a hot-air flue connected with the hot-air drum, a pure-air distributer disposed horizontally and arranged contiguous to the hot- 60 air drum and composed of top and bottom walls, one of the walls being formed by the hot-air drum, said pure-air distributer being open at its perimeter, and means for connect-

ing the pure-air distributer with the exterior of the casing, substantially as described. 65

6. The combination of a casing, a flue, a hot-air drum arranged at the top of the flue and provided with curved partitions disposed radially, the fresh-air distributer located beneath the drum and having radially-arranged 70 curved partitions, and the concentric tubes surrounding the flue and forming passages communicating with the distributer, substantially as described.

7. In a device of the class described, the 75 combination of a casing, a flue depending therefrom, a hot-air drum connected with the flue, a pure-air distributer located beneath the drum, a tube surrounding the flue and forming a passage communicating with the 80 distributer, and a vertically-adjustable water-receptacle mounted on the flue at the exterior of the casing, substantially as and for the purpose described.

8. In a device of the class described, the 85 combination of a casing, a flue depending from the bottom of the casing, a fresh-air passage extending upward from the bottom of the casing, and a vertically-adjustable water-receptacle having a sleeve arranged on the 90 lower portion of the flue, substantially as described.

9. In an incubator, the combination of a 95 casing having a lower egg-compartment, a flue extending entirely through the casing, a horizontal hot-air drum centrally connected with the flue and provided near its side walls 100 with outlets extending through the top of the casing, a horizontal pure-air distributer provided with partitions and located beneath and arranged contiguous to and having its top wall formed by the drum, whereby the air will be heated, and a tube surrounding the flue and communicating with the pure-air distributer, substantially as described. 105

10. In a device of the class described, the combination of a casing provided with means for supplying it with fresh air and having ventilating-openings, a band surrounding the casing and provided with openings adapted to register to a greater or less extent with the ventilating-openings, and means for heating the casing, substantially as described. 110

11. An incubator provided with a pure-air distributer located within the incubator and connected with the exterior thereof, said pure-air distributer being open at its perimeter and provided with partitions, substantially as described. 115

In testimony that I claim the foregoing as 120 my own I have hereto affixed my signature in the presence of two witnesses.

MILTON L. TRESTER.
